(57) **CLAIM**

The ornamental design for a lubricant applicator, substantially as shown and described.

DESCRIPTION

FIG. 1 is an isometric view of a lubricant applicator according to the design.

FIG. 2 is a front view of the lubricant applicator of FIG. 1.

FIG. 3 is a rear view of the lubricant applicator of FIG. 1.

FIG. 4 is right-side view of the lubricant applicator of FIG. 1.

FIG. 5 is left-side view of the lubricant applicator of FIG. 1.

FIG. 6 is a top view of the lubricant applicator of FIG. 1; and,

FIG. 7 is a bottom view of the lubricant applicator of FIG. 1.

Shading lines shown in the drawings are intended to represent the approximate three-dimensional contour of the design, and are not intended to indicate surface decoration.

1 Claim, 7 Drawing Sheets
